CLAIM

The ornamental design for a folder filer, as shown and described.

DESCRIPTION

FIG. 1 is a top perspective view of the folder filer according to our new design, shown with a top flap in a secured configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top perspective view of the folder filer of FIG. 1 shown with the top flap in a tucked configuration.

The broken lines in the drawings illustrate portions of the folder filer that form no part of the claim.

1 Claim, 6 Drawing Sheets# US D1,006,108 S
